(57) **CLAIM**

The ornamental design for a upright network apparatus, as shown and described.

DESCRIPTION

FIG. 1 is a front elevational view of an ornamental design for a upright network apparatus;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof; and,

FIG. 8 is a reference view showing the state of use of the design.

The broken line showing of the environment is for illustrative purposes only and forms no part of the claimed design.
